UNITED STATES PATENT OFFICE.

CARL WILHELM SÖDERBERG, OF NORDSTRAND, NEAR CHRISTIANIA,
NORWAY.

ACETYLENE-GAS GENERATOR.

SPECIFICATION forming part of Letters Patent No. 704,945, dated July 15, 1902.

Application filed July 11, 1899. Serial No. 723,499. (No model.)

To all whom it may concern:

Be it known that I, CARL WILHELM SÖDERBERG, a citizen of Norway, and a resident of Nordstrand, near Christiania, Norway, have 5 invented certain new and useful Improvements in Apparatus for Generating Acetylene Gas, of which the following is a specification.

My invention relates to apparatus for generating acetylene gas, and more especially to 10 that class of such generators in which certain quantities of calcium carbide are from time to time by mechanical means thrown into a body of water contained in a closed vessel communicating with an expandable gas-reservoir.

15 The object of my invention is to provide an improved apparatus of this kind which is simple in construction and operation and which is so constructed and arranged that no 20 air can possibly enter the generator when the apparatus is charged with new carbide and so no gas can escape during charging operation.

It is also the object of my invention to so 25 construct the apparatus that the moving or operating parts of the same are out of contact with the gas, whereby they are prevented from becoming corroded by the action of the gas and whereby easy access to the said parts may be had.

30 My invention consists in the combination, with a container for water having a number of carbide-receptacles placed on its top, of movable covers closing said receptacles to the interior of the water-container and of means for automatically opening and closing said 35 covers through the action of the vertical movement of the expandable gas-reservoir; and it also consists in certain special features of arrangement and construction whereby the 40 aforesaid objects are attained.

In order to fully explain my invention, I 45 have shown in the accompanying drawings an apparatus constructed in accordance with my invention; but it is to be understood that the apparatus shown is only one of the forms 50 which the same may be given.

In the drawings, Figure 1 represents a side elevation, partly in section, of the said improved apparatus. Fig. 2 is a horizontal plan 55 of the same. Fig. 3 is a detail view of one of the carbide-containers. Figs. 4 and 5 are re-

spectively sections on lines 4 4 and 5 5 of Fig. 1 looking toward the left.

While I have shown in Fig. 2 a set of nine carbide-containers arranged in a ring around 55 the axis of the apparatus, I have in Fig. 1 only shown one of these containers, the others being omitted for the sake of simplifying the drawing and more clearly show the operating parts.

60 The apparatus consists of the gas-generator *a* and the gasometer *b*. The gas-generator *a* consists of the water-reservoir, which is funnel-shaped below, as shown at *a'*, and is provided with the discharge-pipe *g*, said reservoir being filled with water to about three-fourths of its height and closed above in gas-proof manner by a top *a²* and wall *a³*, depending into the water, forming a water seal. From this wall extends inwardly and downwardly a deflecting-wall *a⁴*, the lower edges of this wall and the wall *a³* contacting with the supplemental perforated bottom *a⁵*. By means of a tube *c* running into the upper part of the generator the acetylene gas collecting over the water is fed to the gasometer *b*. This may be of the ordinary or any desired construction and comprises a body *b* and movable bell *b'*, the latter being guided by antifriction-rollers *b²*, bearing against vertical 70 posts or rods *b³*. On the upper part of the gas-generator a number of reservoirs *A* are arranged. Nine of these are shown in the drawings for purposes of illustration. They serve as recipients for the carbide. These receptacles are locked in gas-proof manner above by a lid or cover *A'*, secured in place by a suitable clamp *A²*, while a lid *B*, which can be opened, is closely pressed against the under side. Under each carbide-receptacle 75 *A*, which is reduced somewhat toward the upper part for the purpose of better release of the carbide, a cylinder *L* is situated which reaches through the top *a²* of the generator vessel *a* and extends somewhat below the level 80 of the water. The lids or covers *B*, which close the lower ends of the carbide-reservoirs, have each on their axle or shaft *C*, on which they rock, a weighted lever *D*, which rests with its lower edge *d* on a disk *G*, which is pivoted on a pin *F* on the top *a²* of the generator-casing *a*. This disk or plate *G* is

85 90 95 100

turned by means of the rack M, carried by a bracket M', secured to the bell of the gasometer, the toothed wheels N and O, and the face gear-wheel P on the lower side of the disk G 5 when the bell b' sinks. In this action the edges d rub on the disk G, so that the lids B of the carbid-reservoirs are constantly kept locked by the revolving disk G. This disk G is provided with an opening H, which when 10 it reaches a position under the lever D of a cover B allows the lid B to open, as the disk D and the weight of the lid B causes it to fall, thus opening the carbid-reservoir. The contents of the carbid-reservoir A fall into the 15 water vessel a. It is apparent from the above that with every descent of the bell b' a carbid-receptacle A is opened and the contents thereof discharged into the water-reservoir a. The contents of a carbid-receptacle A will de- 20 velop an amount of gas equal to the quantity required to fill the gasometer. The revolution of the disk or plate G occurs only at the descent of the receiver or bell b', while it stands still when the same ascends upon in- 25 troduction of carbid in the water. This action of the mechanism is due to the manner in which one of the toothed wheels N or O is mounted on its axle, one of these wheels be- 30 ing not keyed to the axle, but is loose on the same, being provided with a spring-pawl co- operating with a ratchet-wheel on the axle, so that the toothed wheel may move freely in one direction without taking the axle with it, while in the other direction it moves together 35 with the axle.

In order to ascertain from the outside which receptacles A are still filled with carbid and which are empty, a little indicator K is arranged on each carbid-receptacle A, which indicator is turned by an arm I, connected with the disk G at the point where the carbid-receptacles discharge. In order to permit the downward movement of the bell without a corresponding backward movement of disk 40 G, gear-wheel O is loosely mounted on shaft O' and carries a pawl o, pressed by a spring o' into engagement with a ratchet-wheel o' on the shaft O'. A gravity-pawl g, engaging circularly-arranged ratchet-teeth g' on the 45 under side of the disk G, prevents any backward movement thereof. If this indicator K stands vertical, the reservoir is filled; if horizontal the reservoir is empty. In manipu-

lating the apparatus it is only necessary to feed the emptied carbid-reservoirs at determined intervals again with carbid. 55

The advantages which distinguish the acetylene-gas generator described above over others with automatic action consist, primarily, in the stationary arrangement of the individual 60 carbid-chambers, so that they need not move in the operation of the apparatus. Furthermore, another advantage is obtained for the present apparatus because the various parts effecting the automatic feed of carbid are arranged outside of the gas-room. These mechanisms are, therefore, not exposed to the humidity and the highly destructive influence of the sulfured hydrogen, the phosphureted hydrogen, and the ammonias, &c., developing in the generation of the acetylene. The 65 particular construction of the regulating mechanism renders the whole apparatus rather insensible against shocks and similar influences. Furthermore, carbid cannot under any circumstances be introduced into the 70 water at an improper time. This feed of carbid is regulated by the operation of the apparatus in the most positive manner. Moreover, this apparatus permits no air to penetrate into the generator when the carbid-receptacles are being filled. 75

I claim—

In an acetylene-gas generator in combination, a generator-chamber, a fixed top or cover 80 for the same, a circular row of fixed tubes passing through the said fixed top and dipping into the water of the generator-chamber, carbid-receptacles of less diameter than the said fixed tubes mounted on top of such tubes 85 and provided with air-tight covers at the top, throttle-valves mounted within said tubes and forming movable bottoms for the said receptacles, operating-shafts for holding the said bottoms up against the shoulders formed 90 between the tubes and the receptacles, said operating-shafts having their operative ends placed outside the generator-chamber and means for operating the shafts substantially 95 as described. 100

In witness whereof I have hereunto set my hand in presence of two witnesses.

CARL WILHELM SÖDERBERG.
